UNITED STATES PATENT OFFICE.

EDMUND SCHNABEL, OF NEW YORK, N. Y.

DESIGN FOR A PIANO-CASE.

SPECIFICATION forming part of Design No. 32,112, dated January 16, 1900.

Application filed November 4, 1899. Serial No. 735,833. Term of patent 7 years.

To all whom it may concern:

Be it known that I, EDMUND SCHNABEL, a citizen of the United States, residing in the borough of Bronx, in the city and State of New York, have invented and produced a new and original Design for Piano-Cases, of which the following is a specification, reference being had to the accompanying drawing, forming part hereof.

Referring to the drawing, which is a perspective view of an upright-piano case embodying my invention, the leading and material feature thereof is the curved conformation of the front to form a swell front, the front being most advanced along a central ver-

tical line and curving back toward either side in a rounded ogee curve, so that the front has a bow shape, with a projecting middle portion and backwardly inclining and curving portions on either side terminating in portions 20 nearly in the general plane of the piano-front.

Having thus described my invention, what I claim, and desire to secure by Letters Patent, is—

The design for a piano-case as herein shown 25 and described.

EDMUND SCHNABEL.
